ANVIL ASSEMBLY FOR FORGING HAMMERS
William W. Robbins, Chicago, Ill., assignor to International Harvester Company, Chicago, Ill., a corporation of New Jersey

Filed Dec. 19, 1958, Ser. No. 781,733

2 Claims. (Cl. 78—44)

This invention relates to forging hammers and more particularly to an improved anvil construction of a type used in the forge industry.

One of the most costly maintenance problems in forging hammers has to do with the replacement of anvils. In the conventional forge hammer construction, the anvil consists of a base which is usually firmly supported on a concrete understructure embedded within the floor. The conventional anvil further comprises laterally spaced upper surfaces which support the columns of the hammer. Between the columns the anvil is usually recessed to provide a sow block cradle in which the sow block of the hammer is securely fastened. In addition the sow block usually supports the forging dies and the impact of the dropping hammer is initially absorbed in that portion of the anvil which is disposed immediately below the recess and the sow block. The anvil is generally made of a cast material and it has been found through many years of use that the anvil first deteriorates at the corners of the cradle, the deterioration usually beginning as a crack at the corners, the cracks successively becoming longer and deeper as the anvil is continued to be used. After a period of time, the anvil must be replaced or must be reworked by welding and machining, this operation being very costly and requiring complete removal of the anvil from the understructure which supports the same. The cracks which appear at the corners of the cradle result from the recessed shape of the cradle and the fact that it is at this point where the initial impact of the hammer is absorbed. It is also particularly true in castings that corners present stressed portions which have a tendency to fail more frequently than flat surfaces under conditions of continuous pounding and impact. Thus it is a prime object of this invention to provide an improved anvil assembly constructed and arranged so that a minimum of maintenance is necessary during the life of a forging hammer.

A still further object is the provision of an anvil for forging hammers, the said anvil comprising a plurality of parts which will be simple to disassemble and maintain during the life of the forging hammer.

A still further object is the provision of an improved forging hammer anvil assembly, the said anvil comprising replaceable column supports which are laterally spaced to form a cradle, the said cradle being adapted to receive the initial impacts of the forging hammer, the structure being such that no sharp corners are provided in that the anvil has a flat upper surface which can absorb high degrees of impact over long periods of time without causing cracking of the anvil in regions of the cradle.

These and further objects will become more readily apparent from a reading of the description when examined in connection with the accompanying sheet of drawing.

In the drawing:

FIGURE 1 is a front elevational view of a forging hammer having an improved anvil construction;

FIGURE 2 is a side elevational view of a forging hammer shown in FIGURE 1;

FIGURE 3 is an exploded perspective partial view of an anvil assembly; and

FIGURE 4 is a sectional view taken particularly along the line 4—4 of FIGURE 1.

A forging hammer is generally designated by the refer-

2

ence character 10. The forging hammer 10 comprises an anvil generally designated at 11, the said anvil including a base 12 which may be suitably supported below the ground level within a reinforced pit or understructure (not shown).

5 The anvil 11 comprises at its upper laterally spaced ends outwardly flared portions 13. Furthermore, the anvil includes suitable control rod bosses 14. The anvil includes a flat upper surface 15 having a plurality of spaced vertically extending bores 16 having their open ends opening outwardly on the said surface 15. A column support plate is designated at 17. The column support plate 17 also includes a plurality of bores 18 which are adapted to register with the bores 16 when the support plate 17 is placed into the position shown in 15 the figures. The support plate 17 is rigidly secured to the anvil 11 by means of steel dowel rods 19 which are driven into the bores 18 and 16 in force-fit relation. The column support plate 17 also includes an inner wall 20, the said inner wall diverging outwardly in V-shaped relation. The wall 20 is provided at a central portion with a vertical recess 21. The wall 20 also slopes or tapers upwardly and inwardly with respect to a vertical center line through the anvil 11. Another support plate is also designated at 22. The support plate 22 comprises bores 23 having dowels 24 driven therein in force-fit relation. The dowels 24 also are driven downwardly into the bores 16 of the anvil 11 in force-fit relation to tightly secure the support plate 22 on the top surface 15 of the anvil 11. The support plate 22 also has a tapering wall 25 sloping upwardly and in an inward direction with respect to a vertical center line through the anvil 11. The tapering walls 20 and 25 in effect provide a sow block cradle or saddle generally designated at 26.

A sow block is designated at 27, the said sow block 35 27 having a tapering wall 28, said wall 28 conforming respectively to the wall 20. The sow block 27 also includes a tapered well 29 which may support a forging die (not shown). The sow block further includes another tapering wall 30 which tapers upwardly and inwardly with respect to a vertical center line through the anvil 11. A wedge 31 is tightly driven into a space formed between the wall 30 and the wall 25 and this wedge securely locks the sow block 27 in position. Upwardly extending columns 32 and 33 are suitably secured 40 to the plates 17 and 22 by bolts 32', the said securing means not being pertinent insofar as the invention is concerned. The columns 32 and 33 suitably support guide members 34 which serve to guide a ram 35 having connected thereto a piston rod 36. The piston rod 36 may be connected to a suitable steam or air cylinder in a conventional manner. Or the ram 35 may be suitably connected to a drop type arrangement whereby the ram may drop by gravity, this feature being conventional and not being particularly significant from the standpoint of the invention.

The operation of the forge hammer is unchanged insofar as conventional operation is concerned. During long periods of use, however, only simple maintenance will be required since the anvil is no longer constructed from a single piece, but is in effect, constructed with the column support plates 17 and 22 which are securely connected to the flat surface 15 and these provide the necessary cradle or saddle to retain the sow block 27 in position. Thus the anvil is no longer made integral, as in the conventional design where the recessed cradle has corners which will crack because of the high initial impact which must be absorbed immediately beneath the sow block. Since the corners thus have been eliminated, cracking of the anvil is extremely unlikely in that the stresses are equally distributed throughout the flat surface without stress concentrations occurring in recessed

portions thereof. Furthermore, in the event of damage to either or one of the supporting plates 17 and 22, it is a relatively simple matter to remove the plates and to replace the same.

The shape of the plates 17 and 22 is such that a secure locking arrangement is effected with respect to the sow block 27.

Thus an anvil assembly has been described which will have a long life and which is free of the disadvantages of the conventionally constructed anvil. It is apparent that the objects of the invention have been fully achieved and it must be realized that changes and modifications may be made which do not depart from the spirit of the invention as disclosed or the scope thereof as defined in the appended claims.

What is claimed is:

1. An anvil for use with forge hammers, comprising a base, a flat horizontal top surface on said base, said base including a plurality of bores opening outwardly on said top surface, first and second column support plates positioned in laterally spaced relation on said surface to provide therebetween a sow block saddle, a first support plate having a first inner wall adjacent said saddle, said wall diverging in generally V-shaped fashion outwardly from said recess, said wall tapering downwardly and outwardly with respect to said saddle, said second column support plate having a second inner wall adjacent said saddle tapering downwardly and outwardly with respect to said saddle, a sow block disposed in said saddle, said sow block having an upper die supporting surface and a first tapering wall complementing said first inner wall, a second tapering wall on said sow block, means for secur-

ing said sow block on said saddle including a wedge member engaging said second wall of said sow block and said second inner wall, and means removably securing said plates to said base comprising a plurality of dowels projecting downwardly from said plates into the bores of said base, said plates being adapted to support said columns.

2. An anvil assembly for forge hammers comprising a base having a horizontal supporting surface, said base including a plurality of bores opening outwardly on said supporting surface, first and second column support plates positioned in laterally spaced relation on said surface to provide therebetween a sow block saddle, said plates each having an inner wall tapering generally downwardly and away from said saddle, a sow block removably supported on said cradle, said sow block having laterally spaced tapering walls, one sow block wall conforming to the inner wall of said first plate, a wedge engaging the inner wall of the second plate and the other tapering wall of said sow block whereby said sow block is secured in said saddle, and means removably connecting said plates to said base including members projecting from said plates and engaging said bores in securing relation.
